[57] CLAIM

The ornamental design for a “enclosure stand for a miniature electronic storage device”, as shown and described.

DESCRIPTION

FIG. 1 is a perspective view according to a preferred embodiment of our new design;

FIG. 2 is a front elevational view;

FIG. 3 is a rear elevational view;

FIG. 4 is an upper planar view;

FIG. 5 is a lower planar view; and,

FIG. 6 is a left side elevational view, the right side being a mirror image thereof.

The broken line showing exploded from the article in FIG. 1 is for illustrative purposes only and forms no part of the claimed design. The remaining broken line showings define, but are not included in, the boundaries of the claimed design.
